SPANDREL TRUSS

Robert L. Davison, New York, N. Y., assignor
to John B. Pierce Foundation, New York, N. Y.,
a corporation of New York

Application April 25, 1932, Serial No. 607,389

9 Claims. (Cl. 72—1)

My present invention relates to building construction and more particularly to an exterior wall or spandrel truss construction.

In constructing an ordinary building, such as a house, it is usual to construct the outer wall by utilizing corner risers and intermediate risers, all tied together in a truss construction, arranging in said construction horizontal members for supporting the floor and roof joists. This construction may be varied by utilizing the corner risers and intermediate risers and filling in the space between such risers with a relatively light construction designed to carry and support the outer covering of the building, and the means for supporting the floor or roof joists is attached directly to the risers. These constructions of an ordinary building necessitate the use of relatively heavy material and also a wall of a thickness of such dimension that the effective floor area of the building compared to the actual overall dimensions thereof is relatively small.

Pursuant to my present invention I have aimed to overcome the objectional features of prior constructions and in carrying out my invention I have devised a form of truss construction which not only reinforces the wall material and the insulation so that a relatively structurally weak insulation material may be used with it, but it also decreases the heretofore necessary thickness of the exterior wall, besides adding additional floor area in a given building and above all, reduces the dead load. My invention is adapted to replace the ordinary spandrel beam ordinarily used between columns and is strong enough to carry the entire weight of the wall as well as the floor load.

My improved truss or exterior wall construction consists essentially of a relatively light framework of solid material having the space between the outer limits filled with a wire lattice construction and having extending across the width of the frame and incorporated in the structure a vertically arranged plate of convenient size, and enclosing such structure within any suitable material. The suitable material may be plaster or equivalent substance or any other desirable substance which is suitable as a covering and preferably as an insulating material. With this construction the end member thereof becomes a part of the column or riser and the top member of such truss furnishes a support for the sash and forms the exterior window sill and the interior window sill. In addition, the interior window sill portion may act as a radiator cover or hood and to which may be attached a support for a radiator, thus making it unnecessary to furnish and build such usual appurtenances on the job. The bottom member of the frame forms a window head structure member as well as the usual drip therefor, while the column itself or shelf channels attached to the columns or risers furnish additional bearing support for the truss, thus strengthening the columns and forming jamb members for window frames. Because of the rigidity of the covered truss, it acts as a lateral support for columns or risers and thus reduces the necessary free length of columns and allows the use of smaller columns. Because of the construction of such trusses, they act as a lateral support against wind and earthquake shocks.

The vertically arranged beam interwoven in the truss is designed primarily for supporting beams or floor joists and because of this construction it is merely necessary to provide the floor joists or other like members with cooperating members which slip over and enclose the vertically arranged beam, and in this construction, no bolting of the beam is necessary, and because the interwoven bar is practically at the center of the web of the truss, the actions resulting from the floor joists do not cause any eccentric stress in the structure.

An object of my invention, therefore, is an improved exterior wall and spandrel truss.

Other objects and novel features of the construction embodied in my device will appear as the description of the invention progresses.

In the accompanying drawings illustrating preferred embodiments of my invention,

Fig. 1 is a side elevation of a truss;

Fig. 2 is a plan view of Fig. 1;

Fig. 3 is a sectional side elevation on the line 3—3 of Fig. 1;

Fig. 3a is a detail of a portion of the structure shown in Fig. 3 and showing the vertically arranged floor beam supporting bar attached to the outside of the lattice work;

Fig. 3b is a view similar to Fig. 3a but showing the vertically arranged floor truss supporting bar attached to the other side of the lattice work;

Fig. 4 is an enlarged elevation, partly in section, of the upper right hand corner of the truss shown in Fig. 1;

Fig. 5 is a plan on the line 5—5 of Fig. 4;

Fig. 6 is a side elevation of a portion of the exterior of a building showing a plurality of the trusses constituting my invention in position on the columns or risers;

Fig. 7 is an enlarged elevation, partly in section, of a column or riser to which trusses formed ac-

cording to my invention are attached to either side thereof;

Fig. 8 is a sectional side elevation on the line 8—8 of Fig. 7;

5 Fig. 9 is a sectional plan view on the line 9—9 of Fig. 7;

Fig. 10 is a sectional plan view on the line 10—10 of Fig. 7;

10 Fig. 11 is an enlarged detail of a portion of the upper cord of a truss construction as shown in Fig. 1 and showing the method of applying window jambs to the upper surface thereof;

Fig. 12 is a sectional side elevation on the line 12—12 of Fig. 7;

15 Fig. 13 is a sectional plan view on the line 13—13 of Fig. 12, and

Fig. 14 is a sectional plan view on the line 14—14 of Fig. 12.

20 Referring to the drawings, 18 designates generally a spandrel truss or a unit portion of an exterior wall of a building, such truss comprising essentially an upper cord consisting of a T-shaped member 11 of appropriate dimensions in cross section and of appropriate length, to the upper longitudinal edge of which, as shown in Figs. 2 and 3, at various points along the length thereof, are welded channel members 12, the upper surface of the channel members 12 being co-incident with or lying in the same plane as the upper edge of the T-shaped member 11. Lying parallel to the vertical face of the T-shaped member 11 and having its upper edge preferably welded to the channel members 12, is a U-shaped member 13, the upper surface of this member lying in the same plane as the upper face of the channel members 12 and the upper edge of the T-shaped member 11.

25 The ends of the member 13 are folded over as indicated at 14 to form a partial closure for the 40 end portions thereof. The upper surface of the member 13 is perforated in any suitable manner as indicated at 15 to form a design, while the 45 downwardly extending portion remote from the channel members 12 is perforated to provide a plurality of parallelly arranged holes or perforations 16, all for a purpose to be hereinafter described.

30 At each end of the T-shaped member 11 and 40 extending downwardly therefrom at right angles thereto are angle members 17, the upper ends of such angle members 17 being preferably welded to the T-shaped member 11 and to the end channel members 12. The lower end of the angle members 17 are attached to the ends of a T-shaped member 18 which lies parallel to the T-shaped member 11 and spaced apart therefrom a distance equal to the length of the angle members 17. Secured to the vertical face of the T-shaped member 18 and coincident with the lower edge thereof are channel members 12a, similar in all respects to the channel members 12, above described as being attached to the vertical face of the T-shaped member 11. The angle members 17 on one face thereof, as shown in Fig. 4, are 45 perforated as indicated at 19 and to the inner side of such portion is welded a nut 20, for a purpose to be hereinafter described.

50 The T-shaped members 11 and 18 and the angle members 17 define a substantially rectangular space and this rectangular space is occupied by a lattice work composed of a plurality of rods 21, such rods being welded at their ends to the vertical faces of the T-shaped members 11 and 18 and to the angle members 17. Also, 55 these rods 21 are, where possible, welded to each

other at their points of intersection. Intermediate the ends of the angle members 17, and parallel with the T-shaped members 11 and 18, is a bar or beam 22 of appropriate dimensions, such beam or bar being welded at its ends to the angle members 17 and also being interwoven in the grille or lattice work formed by the rods 21. In addition to being interwoven in the grille or lattice work formed by the rods 21, the bar or beam 22 is preferably welded to the rods 21 at 10 various points along the length of such bar or beam. It is not necessary, however, that such bar or beam 22 be interwoven in the lattice work formed by the rods 21 as shown in Fig. 3a as it is quite within the spirit of my invention to have 15 the bar or beam 22 associated with the lattice work formed by the rods 21 and attached to the rods 21 by welding on one face as shown in Fig. 3a where the bar or beam 22—to distinguish the same from the bar or beam 22—is attached to 20 the one face of the lattice work formed by the rods 21, preferably by welding, and in Fig. 3b where the similar bar or beam 22'' is attached to the opposite side of the lattice work formed by the rods 21 and preferably also by welding. The 25 space within the upper and lower T-shaped members 11 and 18 and including the rods 21 and bar or beam 22 is enclosed in reinforcing and/or insulating material 26. A portion of the construction not embedded in the material 26 is the outer 30 portion of the webs of the T-shaped members 11 and 18.

35 Referring to Fig. 6, there are shown two risers or columns 27 spaced apart a distance equal to the width of the spandrel truss shown in Fig. 1, for example. The members 27 are channel shaped members, as shown in Figs. 9 and 10, for example, and the arms of such channel members 27 are drilled along their length at various points to allow for passage of bolts utilized in 40 bolting a spandrel truss, such as has been described, in position thereon. The spandrel truss is placed in position as shown in Figs. 6 and 7, for example, whereupon the bolt or bolts 28 are 45 passed through the perforations in the vertical edge member of the channel risers 27, a washer 29 being placed under the head thereof, and such bolts screwed into one or the other of the nuts 20 carried on the angle members 17. This 50 bolting of the spandrel trusses 10 takes place until as many have been assembled as desired, with the result that the spandrel trusses extend around the framework of the building in parallel rows, it being assumed of course that care is 55 taken to bring the lowermost spandrel truss in position to allow a floor truss, to be hereinafter described, to be positioned on the bar or beam 22. Assuming this has been done and it is desired to lay the floor truss, a portion of the material 26 adjacent to the bar or beam 22 is cut away as 60 indicated at 30 in Fig. 8 to thereby expose a portion of the length of the bar or beam 22, whereupon the floor truss, consisting of an upper member 31 and a lower member 32 arranged parallel therewith and spaced apart therefrom be of less 65 length than such upper member 31, and connected by diagonals 33 has attached to the lower edge of the upper member 31 an angle member 34, to the angle member 34 is attached an angle member 35, the angle members 34 and 35 defining a slot in which fits the bar or beam 22. The 70 cut away portion 30 is sufficiently large to permit the upper portion 31 of the floor truss to be pushed far enough inward to position the slot over the bar or beam 22, whereupon the truss 75

is lowered to the position shown in Fig. 8, and it will be seen that the lower member 32 thereof engages with the inner face of the material 26 on the spandrel truss 10. The upper end of the spandrel truss 10 in the lower layer has the member 13 thereof lying at a height substantially equal to what will be the lower portion of the window opening and to the member 13 is attached by screws 35a a radiator holder 36 carrying the radiator tubes 37 and 38.

What may be termed the second layer of spandrel trusses 10 that are to be attached to the risers or columns 27 are spaced apart from the lowermost spandrel trusses 10 a distance equal to the height of the desired window opening, as shown in Fig. 8. This opening is designated by the numeral 39 and there is shown in such opening a window structure 40. The window structure 40 may occupy the entire width between adjacent risers or columns 27 as a single window or may be divided into smaller units by means of vertically arranged members 41 extending between the upper edge of the lowermost spandrel truss 10 and the lower edge of the next spandrel truss 10 arranged above the same and defining the opening 39. The members 41 are attached to the now upper and lower arranged channel members 12 and 12a by an angle member 42 that is attached to the members 12 and 12a by screws 43 and to the uprights 41 by screws 44 and bolts 45.

Relatively small window frames may thus be employed and on the risers or columns 27 between the adjacent lower and upper sections of the spandrel truss 10 I have arranged channel members 46 preferably secured thereto by welding along the meeting edges 47 although it is obvious that such channel members 46 may be secured to the risers or columns 27 in any other suitable or desired manner. Such channel members 46 not only act as a side plate or member for a window construction 40, but also, as will be hereinafter described, serve as a means for securing blank panels to constitute a portion of the exterior wall of the building.

This latter feature of my invention is illustrated particularly in Figs. 9, 10 and 12 of the drawings, wherein a blank panel designated generally by the reference numeral 48 is employed to block up a space between adjacent columns or risers 27 where it is not desired to place windows 40. Such blank panel is composed of any suitable insulating material which may be reinforced if desired and which is adapted to fit into the space between adjacent columns or risers 27 and the upper edge of the lower spandrel truss 10 and the lower edge of the next succeeding spandrel truss 10. Secured to the channel member 46 that is attached to the column 27 at various points along the length thereof and at various points along the length of the lower channel member 12a in the lower edge of the upper spandrel truss 10 and to the channel member 12 and upper edge of the lower spandrel truss 10 by screws 51, or in any other suitable manner, are angle members 49. After the positioning of the angle members 49, the blank panel 48 is fitted into the space defined by adjacent risers or columns 27 and the lower and upper spandrel trusses 10 as shown in Figs. 9 and 12, and is secured in position by screws or other suitable fastening means 50 passing through perforations in the angle members 49 and into the body of the blank panel 48. It will be noted on reference to Fig. 9 that the outer portion of the risers or columns 27 has fitted thereon a covering member 52 the outer surface

of which lies in the same vertical plane as the outer surface of the blank panel 48 and such covering member 52 is provided on its lateral edges with extending lips 53 which find a bearing on the outer edge of the columns 27. Also, such lips 53 overlap the outer edge of such columns 27 and between such extending edge and the channel members 46 on each side is arranged a suitable plastic caulking material 54 and to effect a weather-tight joint between the various elements above described. The cover plate 52 has incorporated therein as an integral part thereof, an outwardly extending member 55 which, when the covering member 52 is in position, is in horizontal alignment with the T-shaped members 11 and 18 of adjacent spandrel trusses 10. After the blank panel 48 and the cover plate 52 are positioned as shown in Figs. 9 and 12, I preferably arrange on the lower surface of the T-shaped member 18 and on the upper surface of the T-shaped member 11, angle members 56 to thus secure the blank panel member 48 in position against removal, and for ease in manufacturing and erecting, I preferably attach the angle members 56 to the T-shaped members 11 and 18 by welding although any other form of securing means may be employed.

The covering panels 52 extend through the vertical length of the risers or columns 27 and therefore such covering panels 52 are cut away, as indicated at 57 in Fig. 10, to provide housings for the heads of the bolts 28 which secure the spandrel trusses 10 to the risers or columns 27. Such cut away spaces 57 may be filled with insulating or water-proofing material, if desired, but in any event, it will be noted that the overlapping lips 53 are utilized as securing means for holding an insulating material 58 in position between the risers or columns 27 and the adjacent edges of the spandrel trusses 10.

The spandrel truss may thus be utilized as an exterior wall or wall covering for the building structure and may be made of minimum thickness while affording ample protection against the elements, and by utilizing the proper materials for the enclosing element 28 of the spandrel truss 10 and for the blank panel 48, ample warmth is secured in winter and ample coolness for the interior of the building is secured in summer or warm weather.

Also, the materials 28 and 48 may be readily cut away on the interior thereof in either a vertical or horizontal direction, although preferably, a vertical direction, in order that partitions, such for example as have been described and claimed in my co-pending application Serial No. 591,395, filed February 6th, 1932, and entitled Factory fabricated partition and ceiling construction, or for the attachment of any desired accessories suitable in the erection of a building.

In this connection and referring particularly to Figs. 12, 13 and 14, there is shown at 59 a vertical slot in which is positioned a channel member 60 and which channel member is provided along its inner member 61 with a plurality of spaced perforations 62 which not only act as means through which attaching elements for rigidly attaching the channel member 60 to the spandrel truss 10 or blank panel 48 may be employed, but which also act as a means for positioning various elements utilized in attaching partition members thereto. As pointed out above, the spandrel trusses 10 have the space between the rectangular framework filled with a lattice or mesh composed of rods or bars 24 arranged diagonally

with respect to the length or breadth of the spandrel truss 10 and it is therefore possible to remove a portion of the material 26 or 48 of the spandrel truss 10 or blank panels and thus expose at a plurality of points, in a vertical line, portions of the rods or bars 21. Such a cut away portion is illustrated in Figs. 12 and 14 by the reference numeral 66 and it is obvious that when the portions of the rods or bars 21 are exposed that a U-shaped member 67 may be used to encircle or enclose the exposed portion of the rod or rods 21 whereupon the threaded ends of the legs of such member 67 may be inserted through the proper perforations 62 in the wall 61 of the channel member 60 and the channel member 60 secured in position in the spandrel truss 10 and in the blank panel 48 by the nuts 68. Before this is done, however, and depending upon the character or type of the partition to be utilized, threaded members 69 are secured to the channels 60 by screws 70 as clearly shown in Figs. 12 and 13. With the channel member 60 in position and with the threaded members 69 in the channel thereof and properly positioned vertically, a partition member 71 may be securely attached to the interior of the exterior wall by tie bolts 72 passing laterally through such partition wall as clearly shown in Fig. 13. It is therefore obvious that with my improved spandrel truss that I am not limited to any particular position to which a partition may be attached, because, as stated above, it is always possible to expose a portion of the rods 21 at a plurality of vertically positioned points on the interior of the exterior wall. In my above referred to co-pending application Serial No. 591,395, filed February 6th, 1932, entitled Factory fabricated partition and ceiling construction, for improved means for attaching wall partitions to the exterior wall or to the partitions themselves at any desired points, there are described various forms of structure by which a wall partition may be started at any point of the exterior wall or of a partition and at any other desired point along the exterior wall or on any other partition, and therefore the above described construction with respect to initiating the start of a wall partition 71 to the interior of the exterior wall as shown may be, in accordance with my invention as above referred to in my co-pending application, the terminating point of attachment of the entire wall partition instead of the starting thereof.

From the above, it will be apparent that I have devised a combined exterior wall and spandrel truss, which is unique in construction and functions to support the dead floor load.

My invention also serves to reduce the thickness of the exterior wall while providing the necessary or desirable factor of safety.

From the above, it also appears that I have devised a combined wall and spandrel truss which per se possesses strength sufficient to carry the weight of the floor load and also the form an integral part of the wall proper.

By my combined wall and spandrel truss, the wall material and insulation is reinforced, thereby permitting the wall material and/or its insulation constituent to be reduced relatively to the resulting total wall material.

Supplemental to and independently of the above stated functions, my combined wall and spandrel truss serves also to locate and support a sill for a window, as at the top of each truss unit.

My truss unit also serves to locate and support the usual drip for the window opening.

My truss unit also serves to locate and support a radiator cover or hood. Also, my truss unit serves as a support for a radiator unit.

A special feature of my invention is the capability of my truss unit of being fabricated at a factory, and as thus fabricated provide for the above stated total or lesser number of combinational features.

As indicated above, and as specifically illustrated in the drawings as to one preferred form thereof, the rods or equivalent comprising the open mesh framework extend diagonally relative to the marginal outline of the resulting spandrel truss unit, the individual rods being respectively welded or otherwise secured to one another at spaced locations, as also the ends of the respective rods are welded or otherwise secured to the marginal members, thereby resulting in a combined wall and floor supporting stress equalizing and/or distributing unit.

Wheras I have described my invention by reference to specific forms thereof, it will be understood that many changes and modifications may be made without departing from the spirit of the invention.

I claim.

1. An improved spandrel truss comprising a relatively light open mesh framework of metal, a floor joist supporting beam in addition to the framework extending laterally thereof and parallel to but spaced apart from the upper and lower edges of the truss and means enclosing said structure and forming the same into a unitary structure.

2. In an improved spandrel truss the combination of a unitary slab of insulating and weather-resisting material, a reinforcing framework of relatively light flexible resilient material embedded therein and a floor joist supporting beam intermeshed in the reinforcing framework.

3. An improved spandrel truss comprising a slab of insulating and weather-resisting material, a relatively light framework of resilient material embedded therein and including end members and a floor joist supporting beam intermeshed with the framework and means for securing the ends of the floor joist supporting beam to the end members of the frame.

4. As an article of manufacture, an improved spandrel truss comprising an open mesh framework of metal, angle members secured to the open mesh framework at the margin thereof, and a floor joist supporting beam in addition to the framework extending transversely of the open mesh framework of metal and intermediate the upper and lower horizontal members, said floor joists supporting beam being secured to the open mesh framework and to certain of the marginal angle members.

5. As an article of manufacture, an improved spandrel truss comprising an open mesh framework of metal, angle members secured to the open mesh framework at the margin thereof, the lower horizontal angle member of said angle members serving as a window drip, and a floor joist supporting beam in addition to the framework, extending transversely of the open mesh metal work and intermediate the upper and lower horizontal members, said floor joist supporting beam being secured to the open mesh framework and to certain of the marginal angle members.

6. As an article of manufacture, an improved

spandrel truss comprising an open mesh framework of metal, angle members secured to the open mesh framework at the margin thereof, the upper horizontal angle member of said angle members serving as a window sill, and a floor joist supporting beam in addition to the framework extending transversely of the open mesh metal work and intermediate the upper and lower horizontal members, said floor joist supporting beam being secured to the open mesh framework and to certain of the marginal angle members.

7. As an article of manufacture, an improved spandrel truss comprising an open mesh framework of metal members extending diagonally of the outer margin of the truss and a floor joist supporting beam in addition to the framework extending transversely of the open mesh metal work and intermediate the upper and lower horizontal members, said floor joist supporting beam being secured to the open mesh framework and to certain of the marginal angle members.

8. As an article of manufacture, an improved spandrel truss comprising an open mesh frame-

work of metal members extending diagonally of the outer margin of the truss, the upper horizontal angle member of said outer margin of the truss serving as a window sill, and a floor joist supporting beam in addition to the framework extending transversely of the open mesh metal work and intermediate the upper and lower horizontal members, said floor joist supporting beam being secured to the open mesh framework and to certain of the marginal angle members.

9. As an article of manufacture, an improved spandrel truss comprising an open mesh framework of metal members extending diagonally of the outer margin of the truss, the lower horizontal angle member of said outer margin of the truss serving as a window drip, and a floor joist supporting beam in addition to the framework extending transversely of the open mesh metal work and intermediate the upper and lower horizontal members, said floor joist supporting beam being secured to the open mesh framework and to certain of the marginal angle members.

ROBERT L. DAVISON.
